CLAIM

The ornamental design for a support base for use in automated production, as shown and described.

DESCRIPTION

FIG. 1 is a perspective view of a support base for use in automated production showing my new design;

FIG. 2 is a side elevational view thereof;

FIG. 3 is a top plan view of the base assembly; and

FIG. 4 is a bottom plan view thereof.
The undisclosed vertical panels are the same in appearance as those disclosed in FIGS. 1 and 2.

FIG. I

FIG. 2

FIG. 3
